UNITED STATES PATENT OFFICE.

SAUL SCHULHOFF, OF TRENTON, NEW JERSEY.

RESILIENT HEEL-PAD.

1,279,166.

Specification of Letters Patent. Patented Sept. 17, 1918.

Application filed May 24, 1917. Serial No. 170,586.

To all whom it may concern:

Be it known that I, SAUL SCHULHOFF, a citizen of the United States, residing at Trenton, in the county of Mercer and State 5 of New Jersey, have invented certain new and useful Improvements in Resilient Heel-Pads, of which the following is a specification.

My invention relates to resilient heel-pads 10 or top-lifts for shoes, and is an improvement on the ordinary types, now in use.

In fitting resilient heel pads or top lifts to worn shoe heels, lifts of leather, or similar material, of equal thickness with that 15 of the resilient heel pad are usually removed.

Hitherto it has been difficult to obtain a neat and finished junction line between the leather lift and the resilient heel pad, without the laborious and expensive method of 20 cementing the two surfaces to each other, in addition to the nailing of the one to the other.

Moreover, the use of compressed paper for the inner lifts of leather, has tended to 25 increase the ragged or uneven character of the perimeter of the heel after worn lifts are torn away, and one of the purposes of my invention is to provide for a neat and finished junction or union between the shoe heel 30 and resilient top lift to be applied to the heel.

Heretofore it has been attempted to provide such defined condition in a heel by having the upper surface of the resilient 35 heel slightly convex, but this requires the use of cement as well as a nailing. Still another method has been suggested, that of a heel having an upper surface made deeply concaved and with the lower surface convex.

40 The objection to either of these methods has been mainly that they require special and expensive equipment for their manufacture, in that molds are required of concave and convex formations to produce the same, 45 while according to my invention the resilient heel is produced with the usual equipment in which flat bottom heels are manufactured, by simply substituting a rand plate, which is riveted to the upper plate of the mold 50 for the one now employed, and without change of location of nail-holes and countersunk washers, whereby a flat bottom heel can readily be produced, to closely follow an irregular bottom surface of the shoe heel, 55 and without the requirement of cement to fasten the same to the shoe-heel.

According to my invention and as embracing the essential main feature thereof, the upper surface of the heel is arranged with a central boss, whose upper surface is 60 flat and of the same level as the outer edge of the heel or arranged slightly below the plane of the said edge. The surface of the resilient heel between the centrally located boss and the heel perimeter is arranged with 65 a bounding depression, preferably with the deepest portion nearest the boss and sloping thence upwardly therefrom in the direction of the perimeter of the heel, and the nail holes and countersunk washers located in 70 the formation of the heel about midway between the edges of the boss and the perimeter of the resilient heel, with the result that when such a heel is applied to a shoe-heel and the nails are tightly driven down with 75 a nail-set according to the usual cobbler's practice, there is a reaction set up between the surface of the central boss and the edge of the shoe-heel to cause the heel pad to tightly cling to the shoe heel, even though 80 the surface of the shoe heel is of irregular contour or outline, thus insuring a far more comfortable and symmetrical character of heel-pad.

The nature, scope and characteristic features of my invention as thus hereinbefore defined will be better understood from the accompanying drawings taken in connection with the following description thereof.

In the drawings:—

Figure 1, is a side elevational view of a shoe, showing the shoe-heel with a resilient heel pad in application thereto embodying the essential main features of my said invention.

Fig. 2, is an underneath plan view of the resilient heel pad, showing the detailed arrangement of the upper surface of the same; and

Figs. 3 and 4 are respectively, transverse 100 and longitudinal sectional views on the lines x, x , and y, y , of Fig. 2.

Referring to the drawings a , is the shoe and a^1 the heel thereof.

The resilient heel-pad b , is of the flat type, 105 formed in the upper surface with a centrally arranged boss b^1 , preferably in shape or form conforming to that of the contour or outline of the heel pad b , as clearly illustrated in Fig. 2, and with a depression b^2 , 110 bounding the pad from the location of the boss and extending to the perimeter of the

heel pad b . The deepest portion of the depression being about the boss and decreasing in depth gradually or otherwise, to the perimeter of the heel pad. The boss b^1 , arranged in the upper surface of the said pad b , is flat at b^3 , and preferably of the same level as the outer edge b^4 , of the heel.

The nail holes b^5 , and countersunk-washers b^6 , of the pad b , are located in formation about midway between the edges of the boss b^1 , and the heel-pad perimeter, as clearly shown in Figs. 2 and 4, whereby when the resilient pad b , is applied to the shoe-heel a^1 , and nails are tightly driven down into the said heel with a nail-set, according to the cobbler's practice is established a reaction between the surface of the central boss b^1 , and edge of the shoe-heel a^1 causing thereby the resilient heel-pad to tightly cling to the shoe-heel a^1 , even though the surface of the shoe-heel is irregular or uneven, thus affording greater comfort to

the wearer due to the lessening of strain on the heel-bone by the cushioning effect induced therefrom.

Having thus described the nature and objects of my invention, what I claim as new and desire to secure by Letters Patent is:

A unit resilient flat bottom heel pad having an integral boss located below the plane of the edge and having a depression between the boss and edge of a depth of gradually decreasing dimension from the boss to said edge to thereby provide an edge clinging heel pad, substantially as and for the purposes described.

In witness whereof, I have hereunto set my signature in the presence of two subscribing witnesses.

SAUL SCHULHOFF.
